OIL WELL PUMP

Benjamin F. Schmidt, 450 Fairview St.,
Sierra Madre, Calif.
Filed July 16, 1962, Ser. No. 209,891
17 Claims. (Cl. 103—155)

This invention relates to and has for its primary object the provision of an improved oil well pump which will have an exceptionally long and efficient working life by reason of the novel construction and arrangement of the parts thereof wherein no working part that is exposed to well fluid is operable in rubbing or frictional contact with any other part of the pump or well, thereby making it unnecessary frequently to replace or repair pumps, such as heretofore required in this art.

It is another object hereof to achieve the above objectives by providing an oil well pump in which tubular expansible and contractible elements such as bellows for effecting the pumping action, separate bodies of hydraulic operating fluid and a novel fluid displacing unit operable for displacing the operating fluid to expand and contract the bellows, are carried by a closed and sealed tubular pump body in such a manner that this assembly when operatively positioned with upwardly opening check valves in the tubing of a well, will be operative to effect an efficient pumping operation without having the bellows come into frictional or rubbing contact with any part of the pump or the well and without exposing any interior part of the pump to well fluid.

It is another object of this invention to provide an improved oil well pump such as above described which in one form as here shown, will achieve the objects herein noted, in having upper and lower tubular bellows coupled to opposite ends of a tubular pump body with the bellows and the pump body sealed against entrance of well fluid in a novel manner and containing two bodies of hydraulic operating fluid separated by a piston in the pump body. A piston rod is connected with the piston and extends through and seals the upper end of the upper bellows with a portion of the rod above the bellows adapted to be operatively connected to suitable means above the pump for reciprocating the rod and piston. With this arrangement the upper end of the upper bellows will move with the piston rod and the piston will move so as to displace fluid in the two fluid bodies in such a manner that on the down stroke the upper bellows will collapse and the lower bellows expand, with the reverse of this action taking place on the upstroke, to thereby effect the pumping action with respect to well fluid exteriorly of the bellows, when the pump unit with a pair of upwardly open check valves are suitably positioned in the well tubing.

It is a further object of this invention to provide a pump such as next above described which in one form may include in connected relation therewith a foot valve below the lower bellows adapted to seat in well tubing, and wherein an annular and upwardly opening check valve assembly is carried by and surrounds the tubular pump body between the two bellows so as to form a seal with the pump body and a seat in the well tubing, thereby providing a complete pump unit including the valves and which may be positioned in well tubing ready for operation when the valves carried thereby are seated in the well tubing, and also providing for ready removal of the complete pump unit from the well when desired.

It is another object hereof to provide a pump of the character described which readily lends itself to being lowered in a well and removed therefrom as a complete unit on a wire line since it may be operated by a suitable motor operatively connected with the piston rod rather than by a conventional sucker rod, although a sucker rod could be used if desired.

2

Another object hereof is the provision of a pump such as described having a novel arrangement which prevents "sanding up" of the foot valve and related parts as well as detrimental exposure of other parts of the pump to sand and well fluid and at the same time controls in an efficient manner the flow of well gas with respect to portions of the pump so that this gas will not interfere with the desired pumping operation.

Another object of this invention is the provision in an oil well pump of the character described of novel means for filling the two bellows and the pump body at the factory with the two bodies of hydraulic operating fluid which are displaced by the piston to effect expansion and contraction of the bellows, this filling operation being made possible by use of a hollow portion of the piston rod communicating with the fluid chamber above the piston and in the upper bellows. The portion of this hollow rod above the upper bellows and the lower end of the lower bellows have filling openings, both of which are normally closed by plugs removably fitted therein.

Another object of this invention is to provide in a pump of the character described novel means for guiding the bellows in the expansion and contraction thereof so as to avoid frictional engagement thereof with any part of the well or pump and to prevent buckling of the bellows, it being noted in this connection that the internal and external pressures to which the bellows are subjected in a well are substantially equal so that rupture or other failure thereof due to fluid pressure are prevented.

Other objects and advantages of the invention will be hereinafter described or will become apparent to those skilled in the art, and the novel features of the invention will be defined in the appended claims.

Referring to the drawings:

FIG. 1 is a fragmentary elevational view partly in section of a pump embodying the present invention as it would appear when positioned in a well;

FIG. 2 is a fragmentary vertical sectional view on an enlarged scale of the upper portion of the pump;

FIG. 3 is a fragmentary vertical sectional view on the same scale as FIG. 2, of that lower section of the pump that is joined at its upper end to the lower end of the upper pump section shown in FIG. 2;

FIG. 4 is a vertical sectional view of the means for securing the upper expansible and contractible pumping element of the pump to the reciprocable pump rod and for positively sealing the upper end of this pumping element;

FIG. 5 is an enlarged sectional view taken on the line 5—5 of FIG. 2;

FIG. 6 is an enlarged sectional view taken on the line 6—6 of FIG. 3;

FIG. 7 is an elevational view of the valve unit shown in FIG. 6, with a surrounding portion of the unit shown in section;

FIG. 8 is an enlarged perspective view of a conical gas escape check valve;

FIG. 9 is an enlarged sectional view taken on the line 9—9 of FIG. 3; and

FIG. 10 is an enlarged sectional view taken on the line 10—10 of FIG. 3.

Referring more specifically to the drawings, A designates an oil well pump embodying the present invention as it would appear when positioned in the tubing B of an oil well together with a foot valve C below the pump and an upwardly opening check valve assembly D located between the ends of the pump in surrounding and sealing engagement with the pump as well as in sealing contact with the tubing. The pump A is spaced circumferentially from the well tubing and thereby provides above and below the check valve assembly D, annular flow passages E and F for well fluid, the check valve D

permitting flow of well fluid from the lower passage F into the upper passage E in response to operation of the pump A in a manner which will be hereinafter described.

The pump A includes a sectional tubular pump body 1 extending above and below the upwardly opening check valve assembly D which, as here shown, may be carried by the pump body 1 as a part of the pump and has sealing engagement with a seat 2 formed, as best shown in FIG. 3, internally of a joint section 3 of the well tubing B. Likewise, the foot valve C may be carried by a tubular extension 4 of the pump body 1 for sealing contact with an internal seat 5 provided in a lower section 6 of the well tubing. With this arrangement the complete pump may be readily positioned in the well tubing and as readily removed therefrom.

The tubular pump body 1 is open at opposite ends and is divided into upper and lower sections by a reciprocable piston 8 operable in a cylinder or barrel portion 9 of the pump body.

Upper and lower tubular expandable and contractible pumping elements here shown as a bellows 10 and 11 and made of synthetic rubber or other suitable material that is chemically inert to well fluid, are connected with opposite ends of the pump body 1 so as to form therewith a pair of sealed elongate chambers 14 and 15 separated by the piston 8. Each of these sealed chambers contains a body of hydraulic fluid which, in response to reciprocation of the piston 8, will cause the bellows 10 and 11 to expand and contract longitudinally in the well tubing. As the bellows 10 and 11 constitute upper and lower end portions of the pump and are spaced circumferentially from the well tubing with their exterior surfaces exposed to well fluid in the tubing, expansion and contraction of the bellows will effect, as will be herein-after described, a pumping action effective to pump well fluid from the well.

As a means for reciprocating the piston 8 to effect longitudinal expansion and contraction of the bellows 10 and 11, a piston rod 16 is connected with the piston and extends through the upper bellows 10, which latter at its upper end is connected with the piston rod so as to be movable therewith and so as to form a seal excluding entrance of well fluid between the upper end of the bellows and the piston rod. The piston rod may be connected to a motor operated drive unit, not shown, that may be lowered with the pump into the well, this unit being electrically, pneumatically or hydraulically operated and in effect a part of the complete pump. If desired, the piston rod 16 may be sucker rod operated, although a motor operated drive unit connected with the pump to be lowered therewith in the well as above described may be preferred as a more efficient operating means for the pump, since it may be lowered and raised with the pump on a wire line.

Before describing the construction of the elements of the pump more specifically and the means whereby the two bodies of operating fluid sealed therein and separated one from the other may be placed in the pump, it should be noted that the two bellows in being longitudinally expanded and contracted do not come in contact with the well tubing and that the piston 8 and interior of the cylinder portion 9 of the pump body 1 as well as the entire interior of the pump do not come in contact with the well fluid and are therefore protected against wear and the abrasive action of sand in the well fluid. It is also important to note that the pump here shown may be prepared ready for use at the factory with the two separate bodies of hydraulic operating fluid sealed therein and the entire pump so sealed that in the shipping or handling thereof it may be disposed in any position without disturbing the operative connection and arrangement of the elements thereof or interfering with the required separation of the two bodies of operating fluid.

The tubular pump body 1 as here shown, includes in addition to the cylinder portion 9 which is intermediate

the ends of the body, a fitting 17 screwed onto the upper end of the cylinder portion 9 and having a central tubular guide member 18 through which the piston rod 16 is slid able. The fitting 17 also provides for connection of the lower end of the upper bellows 10 to the upper end 5 of the cylinder portion 9, the bellows being clamped so as to be sealed around the fitting by suitable clamping means 19 as shown in FIG. 2. The tubular guide 18 is held in the fitting by means of webs 20 and passages 21 formed between the webs to communicate the upper portion of the cylinder portion 9, in other words the chamber 14 above piston 8, with the interior of the bellows 10.

The means for securing the upper end of the bellows 10 with the piston rod 16 includes a partially split tubular fitting 23 that is clamped on this rod by a clamping screw 24 threaded thereto to bind the split portion of the fitting to the rod as shown in FIG. 2. A sealing ring 25 in the fitting 23 seals against the rod 16 to prevent well fluid from leaking between the rod and the fitting. The lower end of the fitting 23 is provided with a flange 26 over which the upper end of the upper bellows 10 is fitted so as to be clamped around the fitting in sealed engagement therewith by suitable clamping means 27.

Means are provided to guide the upper bellows 10 to keep it from buckling and, as here shown, comprises a number of disks 28 axially spaced in the bellows and surrounding the piston rod 16 with their outer edges engaged with the inner surfaces of the surrounding wall of the bellows to hold this wall distended, there being openings 30 in the disks 28 to permit free flow of the operating fluid through the disks 28.

As shown in FIGS. 1 and 2, the upper end of the piston rod 16 may be threadedly coupled by upward extensions 32 and 33 thereof to a sucker guide member 34 having flow grooves 35 thereon if the piston rod is to be sucker rod operated. If otherwise operated as by a motor driven means lowered into the well as hereinbefore mentioned, the piston rod 16 may be connected in any suitable manner to such drive means.

If desired, the piston rod 16 may be tubular to provide a chamber 37 therein for containing some of the operating fluid confined in upper bellows 10 and in the upper chamber 14 in the cylinder portion 9. This tubular form of the piston rod also facilitates the introduction into the upper chamber 14 and upper bellows 10 of the proper amount of operating fluid that is confined above the piston 8. The rod 16 is provided with ports 38 adjacent the upper side of the piston 8 for communicating the chamber 37 with upper chamber 14 in the cylinder portion 9, as shown in FIG. 2, and at its upper end the rod is closed by a removable plug 40. Thus, on removing the plug 40 the chamber 14 and the upper bellows 10 may be filled as required through the upper end of the rod 16. In this connection, it should be noted that the fitting 23 as shown in FIG. 4 is provided with an air vent passage 23' for venting air from the bellows 10 in filling this bellows. After the filling operation a plug 23" is employed to seal this vent passage 23'.

The piston 8 as shown in FIG. 2, may be of any suitable form provided it will prevent flow of the operating fluid past it in the cylinder portion 9 of the pump. Fixed on the upper side of the piston in surrounding relation to the pump rod 16 is a fitting 41 supporting a cushioning stop ring 42 adapted to abut the fitting 17 at the upper end of the cylinder portion 9 to limit upward movement of the piston. The piston 8 is limited as to its downward movement by a stop member 43 secured to the lower side thereof by means of a threaded shank member 44 projecting from the stop member 43 and extending through the body 45 of the piston so as to be threaded into the lower end of the piston rod. This stop 43 and the threaded shank member 44 secures the piston carried elements together and also connects the piston rod to the piston. In addition, the stop member 43 is disposed so as to contact a cushion ring 48 which,

as shown at the top of FIG. 3, is positioned at the lower end of the cylinder portion 9 to limit downward movement of the piston with a cushioning action.

With reference to FIG. 3 which shows the construction of the lower section of the pump, it will be seen that the lower end of the cylinder portion 9 of the tubular pump body 1 has a threaded fitting 50 thereon in sealed engagement therewith and which has a threaded opening 51 therethrough receiving the threaded upper end of the lowermost tubular section 52 of the tubular pump body 1. This tubular section 52 extends through the upwardly opening check valve D and at its lower end is flanged as at 53 and has the upper end of the lower bellows 11 clamped around the end 53 by means of suitable clamping means 54 which forms a fluid tight seal of the upper end of this bellows.

The lower end of the lower bellows 11 is closed by means of a plug 56 removably threaded into the bore of an annular closure member 57 within the bellows. This closure member has a threaded shank 58 projecting from the lower end of the bellows for reception of a nut 59 that is threaded on the shank so as to clamp the bellows between the nut and the inner flared end of the closure member 57 thereby sealing the lower end of the bellows. On removal of the plug 56 the bellows 11 and the lower chamber 15 which includes lowermost tubular section 52 of the pump body 1 and the portion of the cylinder 9 below piston 8 may be filled as required with operating fluid. This filling may be effected at the time the pump unit 1 is being prepared for use and completed at the factory and may be easily carried out by inverting the pump assembly so that the bellows 11 is uppermost, the plug 56 after the filling being replaced to seal in the operating fluid.

The check valve assembly D as shown in FIGS. 3 and 7, comprises an annular section 61 that surrounds the tubular section 52 of the pump body 1 with the upper end of the upper section 61' thereof abutting the fitting 50 and sealed thereagainst by means of the sealing ring 62. The lower section 61" of the body 61 is supported by the seat 2 in the well tubing, there being a sealing ring 64 between the seat 2 and lower section 61" which latter has a bevelled lower end removably wedged in the seat 2. The lower section 61" is supported by a tubular member 66 surrounding the section 52 of the pump body 1 and resting on a shoulder 67 on section 52 and abutting the upper section 61'. A flow passage 68 is provided through the sectional body 61 and terminates short of the upper end thereof in lateral ports 69 in the upper section 61' and which will discharge well fluid into the upper annular passage E above the check valve assembly D during a pumping operation. Ports 70 formed in tubular portions 71 between the sections of the body 61 afford communication between passage 68 and the lateral ports 69, the ports 70 being normally closed by the ball valves 72 which seat on the upper ends of the tubular portions 71 and open the ports 70 in response to the pressure of well fluid being pumped from the lower annular passage F in the well tubing.

As shown in FIGS. 1 and 3, the tubular extension 4 at the lower end of the pump body 1 and to which the foot valve C is attached, is connected with an annular enlargement 74 adjacent the lower end of the pump body section 52 to which the lower bellows 11 is connected. This tubular member 4 surrounds the bellows 11 which is circumferentially spaced therefrom and so maintained by one or more annular disks 75 surrounding the bellows, there being openings 76 in the disks to permit free flow of gas and well fluid therethrough, since the interior of the tubular member 4 defines a chamber 77 for containing well fluid that has entered from the foot valve through a port 78 in the valve and this fluid will be pumped out of the chamber 77 through ports 79 into the annular passage F in the well tubing B in response to the pumping action of the lower bellows. In this connection, it should

be noted that the foot valve C when unseated permits well fluid to enter the annular passage F through lateral ports 81.

Gas that enters the chamber 77 will be relieved through vents 81 in the enlargement 74 at the lower end of the lower tubular section 52 of the pump body 1, there being an annular conical closure 83 on the conical upper end of the enlargement 74 for normally closing the vents 81 and which opens only in response to pressure of gas seeking escape through the vents 81.

In the operation of the pump on the down stroke of the piston 8 the two bodies of hydraulic fluid on opposite sides of the piston are actuated and the upper end of the upper bellows 10 moves downward with the piston rod 16 and some of the upper body of operation fluid is withdrawn from the bellows 10 into the cylinder portion 9 with the descending piston thereby longitudinally collapsing and extending the upper bellows. At the same time some of the lower body of fluid is forced by the descending piston 8 into the lower bellows 11 and causes expansion thereof. This expansion of the lower bellows 11 causes well fluid surrounding it to be forced out of the chamber 77 through ports 79 and 80 into the annular passage F, thence upwardly in the well tubing B through the check valve assembly D. In passing through the ports 80 the well fluid tends to wash sand and corrosives upwardly away from the foot valve.

On the upstroke of the piston 8, some of the body of fluid above the piston 8 is forced upwardly into the upper bellows 10 causing it to expand and force upward in the well tubing, the well fluid entrapped above the check valve assembly D, such well fluid reaching the top of the well upon continued operation of the pump.

During the upstroke of the piston 8, it draws some of the lower body of operating fluid below the piston into the lower cylinder portion 9 of the pump from the lower bellows 11 which is thereby collapsed and creates a suction causing well fluid to rise above the foot valve C.

It should be noted that if the well in which the pump is installed is free of sand, the tubular member 4 attached to the lower end of the tubular pump body may be omitted and the lower bellows will then be operable in the lower part of the well tubing with a suitable foot valve, not shown, installed below the lower bellows in the tubing. The tubular member 4, as here provided, is most effective in sandy wells, since when the bellows 11 therein is expanded, the well fluid in the member 4 is forced down by the bellows rather than upwardly, and with the velocity that sets up a turbulence and lifts from the foot valve C any sand that may have settled thereon, thereby forcing the sand away from the valve through the ports 79 and 80. Moreover, gas entrapped in the member 4 will escape through the vents 81 as the pressure of the gas lifts the closure 83, which latter is normally closed and prevents sand and well fluid from entering the vents 81.

It should be noted that the amount of operating fluid constituting the upper and lower bodies of fluid separated by the piston 8 is such that an adequate amount of such fluid will remain in the bellows to prevent complete collapse thereof when the piston 8 reaches the upper and lower limits of its stroke. In this connection, it should be noted that internal and external pressures on the bellows are substantially equal so that rupture and complete collapse of the bellows are prevented. The annular member 75 surrounding the lower bellows 11 and the disks 28 within the upper bellows prevent lateral buckling of the bellows and, therefore, prevent damage thereof.

It will now be apparent that an oil well pump constructed in accordance with the present invention is characterized by the novel features as follows:

(1) Actuation of expandible and contractible pumping elements by two separate bodies of operating hydraulic fluid in closed circuits separated by a reciprocable piston

and cylinder unit which is sealed against exposure to well fluid and operates with less wear and friction than encountered with reciprocable well pumps as heretofore made.

(2) The expandible and contractible elements are simultaneously operated one to expand and the other to contract on each stroke of the piston.

(3) The securing of the upper end of the upper expandible and contractible pump element to a reciprocable piston rod for movement with the latter and for forming a seal excluding entrance of well fluid into the pump unit around the piston rod.

The above noted and other advantages which are hereinbefore set forth establish that the pump hereof constitutes a noteworthy improvement in bellows type pumps as heretofore made.

While the pump unit of this invention as produced at the factory is operable as made in any well, it is to be understood that an operable pump assembly embodying this invention requires that the pump unit be positioned in well tubing with the two bellows exposed exteriorly to the well fluid as here shown and that suitable means be provided for reciprocating the piston rod and piston of the pump unit as hereinbefore described.

It is also to be understood that the foot valve C and upwardly opening check valve assembly D here shown as parts of the pump unit that may be positioned in a well with the pump unit, could be of any suitable form other than here shown and carried by the well tubing, in which case the pump unit would seat thereon in a manner which is well known in this art.

While specific structural details have been shown and described, it should be understood that changes and alterations may be resorted to without departing from the spirit of the invention as defined in the appended claims.

I claim:

1. In a well pump: a tubular pump body; expandible and contractible bellows coupled to the ends of said pump body to constitute sealed expandible and contractible extensions of said pump body in fluid flow communication only with the interior of said pump body; a fluid displacement member in said pump body movable toward and away from said ends of said pump body; separate bodies of hydraulic operating fluid in said body and said bellows separated by said fluid displacement member and operable to expand and contract said bellows in response to said movements of said fluid displacement member; means for effecting said movements of said fluid displacement member; means operatively associated with said pump body operable in response to said expansion and contraction of said bellows for directing well fluid upwardly around the exterior of said pump body in the well in which the pump is operated; and an upwardly opening check valve assembly surrounding said pump body above said last named means operable for retaining pumped fluid above it.

2. In a well pump: a tubular pump body; expandible and contractible bellows coupled to the ends of said pump body to constitute sealed expandible and contractible extensions of said pump body in fluid flow communication only with the interior of said pump body; a fluid displacement member in said pump body movable toward and away from said ends of said pump body; separate bodies of hydraulic operating fluid in said body and said bellows separated by said fluid displacement member and operable to expand and contract said bellows in response to said movements of said fluid displacement member; reciprocable means extending through one of said bellows and connected thereto and to said fluid displacement member for effecting said movements of said fluid displacement member; said bellows to which said reciprocable means is connected being movable therewith; and two upwardly opening check valve assemblies operatively associated with said pump body; one of said check valve assemblies being operable to permit well fluid to rise thereabove in response to said actuation of said bellows;

and the other of said check valve assemblies surrounding said pump body above the first mentioned check valve assembly for holding pumped fluid thereabove.

3. In a well pump for operation in well tubing: a tubular pump body; expandible and contractible bellows coupled to the ends of said pump body to constitute sealed expandible and contractible extensions of said pump body in fluid flow communication only with the interior of said pump body; a fluid displacement member in said pump body movable toward and away from said ends of said pump body; separate bodies of hydraulic operating fluid in said body and said bellows separated by said fluid displacement member and operable to expand and contract said bellows in response to said movements of said fluid displacement member; means for effecting said movements of said fluid displacement member; a foot valve depending from the exterior of the lower end of said pump body; and an annular upwardly opening check valve assembly surrounding and carried by said pump body between said bellows and adapted to seal against the well tubing in which said pump body is disposed.

4. In a well pump for operation in well tubing: a tubular pump body; hollow expandible and contractible elements coupled to the ends of said pump body so that the interiors thereof are in communication with the interior of said pump body and the exterior only will be exposed to well fluid; a fluid displacement member in said pump body movable axially therein; separate bodies of hydraulic operating fluid confined in said body and said expandible and contractible elements and separated by said fluid displacement member and operable to expand and contract said expandible and contractible elements in response to axial movement of said fluid displacement member; means for effecting said movement of said fluid displacement member; a foot valve connected to and disposed below the lower end of said pump body; and an upwardly opening check valve assembly surrounding and carried by said pump body between said expandible and contractible elements and adapted to seal against the well tubing.

5. In a pump assembly: a tubular pump body adapted to be positioned in well tubing; expandible and contractible bellows coupled to the ends of said pump body to form sealed extensions of said pump body; a reciprocable piston in said body; a body of hydraulic fluid on each side of said piston and in said bellows; a reciprocable piston rod extending through one of said bellows in sealed engagement therewith and connected thereto so that said one bellows is movable therewith; said piston rod extending into said body and being connected to said piston; and a pair of valve assemblies exteriorly of said body and carried thereby adapted to seal against said well tubing; said pump body and said bellows being circumferentially spaced from said well tubing to provide an annular passage for well fluid between said body and said well tubing for intaking well fluid through one of said valve assemblies and discharging well fluid through the other of said valve assemblies in response to actuation of said bellows.

6. An oil well pump comprising: a tubular pump body; a tubular upper bellows coupled at one end to one end of said pump body; means sealing the other end of said upper bellows; a tubular lower bellows coupled at one end to the other end of said pump body; means sealing the other end of said lower bellows; said pump body and said two bellows constituting a sealed pump unit adapted to be positioned in tubing of a well in spaced relation thereto to define therebetween a flow passage for well fluid; means providing below said lower bellows a foot valve assembly for intaking well fluid into said flow passage; means providing an upwardly opening check valve assembly in said well tubing in surrounding relation to said pump body between said upper and lower bellows and for forming a seal with said body and said well tubing; fluid displacing means movable in said pump body between said bellows and forming therein two sealed chambers sep-

arated by said displacing means and with each chamber including one of said bellows; separate bodies of hydraulic fluid sealed in said chambers and operable in response to movements of said displacing means to expand and contract said bellows; and operating means connected to said displacing means operable from the exterior of said pump body for moving said displacing means to displace said fluid bodies and thereby expand and contract said bellows.

7. An oil well pump comprising: a tubular pump body; a tubular upper bellows coupled at one end to one end of said pump body; means sealing the other end of said upper bellows; a tubular lower bellows coupled at one end to the other end of said pump body; means sealing the other end of said lower bellows; said pump body and said two bellows constituting a sealed pump unit adapted to be positioned in tubing of a well in spaced relation thereto to define therebetween a flow passage for well fluid; means providing below said lower bellows a foot valve assembly for intaking well fluid into said flow passage; means providing an upwardly opening check valve assembly in said well tubing in surrounding relation to said pump body between said upper and lower bellows and for forming a seal with said body and said well tubing; fluid displacing means movable in said pump body between said bellows and forming therein two sealed chambers separated by said displacing means and with each chamber including one of said bellows; separate bodies of hydraulic fluid sealed in said chambers and operable in response to movements of said displacing means to expand and contract said bellows; and means connected to said displacing means and extending outwardly through said upper bellows in sealed relation thereto for connection with means for effecting said movements of said displacing means.

8. An oil well pump comprising: a tubular pump body; a tubular upper bellows coupled at one end to one end of said pump body; means sealing the other end of said upper bellows; a tubular lower bellows coupled at one end to the other end of said pump body; means sealing the other end of said lower bellows; said pump body and said two bellows constituting a sealed pump unit adapted to be positioned in tubing of a well in spaced relation thereto to define therebetween a flow passage for well fluid; means providing below said lower bellows a foot valve assembly for intaking well fluid into said flow passage; means providing an upwardly opening check valve assembly in said well tubing in surrounding relation to said pump body between said upper and lower bellows and for forming a seal with said body and said well tubing; fluid displacing means movable in said pump body between said bellows and forming therein two sealed chambers separated by said displacing means and with each chamber including one of said bellows; separate bodies of hydraulic fluid sealed in said chambers and operable in response to movements of said displacing means to expand and contract said bellows; an operating member connected to said displacing means and movable for effecting said movements of said displacing means; said operating member being extended through said upper bellows for connection with means for effecting said movement thereof; and means connecting said upper bellows to said operating member for movement therewith.

9. An oil well pump comprising: a tubular pump body; a tubular upper bellows coupled at one end to one end of said pump body; means sealing the other end of said upper bellows; a tubular lower bellows coupled at one end to the other end of said pump body; means sealing the other end of said lower bellows; said pump body and said two bellows constituting a sealed pump unit adapted to be positioned in tubing of a well in spaced relation thereto to define therebetween a flow passage for well fluid; means providing below said lower bellows a foot valve assembly for intaking well fluid into said flow passage; means providing an upwardly opening check valve assembly in said well tubing in surrounding relation to said pump body

between said upper and lower bellows and for forming a seal with said body and said well tubing; a piston reciprocable in said pump body between the ends of said pump body dividing said body into two sealed chambers each of which includes one of said bellows; means providing for the introduction into said chamber and bellows and the sealing therein of two bodies of hydraulic fluid separated by said piston and which fluid bodies, upon reciprocation of the piston, will cause expansion and contraction of said bellows; and a piston rod connected with said piston and extending through and above the upper end of said upper bellows in sealed engagement therewith to afford connection thereof with means for reciprocating said rod and said piston.

10. An oil well pump comprising: a tubular pump body; a tubular upper bellows coupled at one end to one end of said pump body; means sealing the other end of said upper bellows; a tubular lower bellows coupled at one end to the other end of said pump body; means sealing the other end of said lower bellows; said pump body and said two bellows constituting a sealed pump unit adapted to be positioned in tubing of a well in spaced relation thereto to define therebetween a flow passage for well fluid; a tubular member connected to the lower end of said pump body in surrounding and circumferentially spaced relation to said lower bellows and likewise spaced from said well tubing; a foot valve assembly carried by the lower end of said tubular member below said lower bellows; said foot valve assembly having ports for intaking well fluid into said member as well as into said flow passage in the well tubing; said tubular member having gas outlet port means; an upwardly opening closure normally closing said gas outlet port means; an annular upwardly opening check valve assembly surrounding said pump body between the ends of said pump body and operable to seal against the well tubing and the pump body; a piston reciprocable in said pump body between the ends of said pump body dividing said body into two sealed chambers each of which includes one of said bellows; means associated with said bellows providing for the introduction into said chamber and bellows and the sealing therein of two bodies of hydraulic fluid separated by said piston and which upon reciprocation of the piston will cause expansion and contraction of said bellows; and a piston rod connected with said piston and extending through and above the upper end of said upper bellows in sealed engagement therewith to afford connection thereof with means for reciprocating said rod and said piston.

11. An oil well pump comprising: a tubular pump body; a tubular upper bellows coupled at one end to one end of said pump body; means sealing the other end of said upper bellows; a tubular lower bellows coupled at one end to the other end of said pump body; means sealing the other end of said lower bellows; said pump body and said two bellows constituting a sealed pump unit adapted to be positioned in tubing of a well in spaced relation thereto to define therebetween a flow passage for well fluid; means providing below said lower bellows a foot valve assembly for intaking well fluid into said flow passage; means providing an upwardly opening check valve assembly in said well tubing in surrounding relation to said pump body between said upper and lower bellows and for forming a seal with said body and said well tubing; fluid displacing means movable in said pump body between said bellows and forming therein two sealed chambers separated by said displacing means and with each chamber including one of said bellows; separate bodies of hydraulic fluid sealed in said chambers and operable in response to fluid displacement movements of said displacing means to expand and contract said bellows; and operating means connected to said displacing means operable from the exterior of said pump body for moving said displacing means to displace said fluid bodies and thereby expand and contract said bellows; said

fluid displacement means comprising a reciprocable piston and cylinder unit intermediate the ends of said pump body; said operating means for said displacement means comprising a piston rod.

12. An oil well pump comprising: a tubular pump body; a tubular upper bellows coupled at one end to one end of said pump body; means sealing the other end of said upper bellows; a tubular lower bellows coupled at one end to the other end of said pump body; means sealing the other end of said lower bellows; said pump body and said two bellows constituting a sealed pump unit adapted to be positioned in tubing of a well in spaced relation thereto to define therebetween a flow passage for well fluid; means providing below said lower bellows a foot valve assembly for intaking well fluid into said flow passage; means providing an upwardly opening check valve assembly in said well tubing in surrounding relation to said pump body between said upper and lower bellows and for forming a seal with said body and said well tubing; fluid displacing means movable in said pump body between said bellows and forming therein two sealed chambers separated by said displacing means and with each chamber including one of said bellows; separate bodies of hydraulic fluid sealed in said chambers and operable in response to fluid displacement movements of said displacing means to expand and contract said bellows; operating means connected to said displacing means operable from the exterior of said pump body for moving said displacing means to displace said fluid bodies and thereby expand and contract said bellows; said fluid displacement means comprising a reciprocable piston and cylinder unit intermediate the ends of said pump body; said operating means for said displacement means comprising a piston rod; said piston rod having a tubular portion extending into and from said upper bellows and having a filling opening in the portion above said upper bellows; a plug removably fitted in said filling opening; and the means for sealing said lower bellows including a filling opening and a plug removably fitted in said last named filling opening.

13. In a well pump; a tubular pump body; expandable and contractible bellows coupled to said pump body in fluid flow communication with the interior of said pump body; a fluid displacement member movable in said pump body for displacing fluid therein; separate bodies of hydraulic operating fluid confined in said pump body and said bellows and separated by and displaceable upon movements of said fluid displacement member so as to expand and contract said bellows; means for effecting said movements of said fluid displacement member; and upwardly opening check valve assemblies operatively associated with said pump body; one of said check valve assemblies being located to permit well fluid to rise thereabove exteriorly of said pump body upon actuation of said bellows; the other of said check valve assemblies surrounding the exterior of said pump body above one valve assembly.

14. In a well pump: a tubular pump body; expandable and contractible bellows coupled to said pump body in fluid flow communication with the interior of said pump body; a fluid displacement member movable in said pump body for displacing fluid therein; separate bodies of hydraulic operating fluid confined in said pump body and said bellows and separated by and displaceable upon movements of said fluid displacement member so as to expand and contract said bellows; an upwardly opening check valve assembly carried by said pump body between said bellows and adapted to form a seal with well tubing in which the pump is positioned; and a foot valve assembly connected to said pump body and disposed below the lower end thereof.

15. In a well pump: a tubular pump body; a piston

reciprocable in said pump body; a piston rod connected to said piston; a plurality of expandable and contractible elements coupled to said pump body in fluid flow communication with the interior of said pump body; means connecting one of said expandable and contractible elements with said piston rod for movement therewith; operating oil in said pump body and said expandable and contractible elements; said oil being disposed on opposite sides of said piston; means on said piston rod for connection with means for reciprocating said rod and said piston; an upwardly opening annular check valve assembly surrounding said pump body for confining thereabove exteriorly of said pump body well fluid pumped thereabove; and a second upwardly opening check valve operatively associated with said pump body operable in response to expansion and contraction of the lowermost of said expandable and contractible elements for admitting well fluid to pass through said annular check valve assembly.

20 16. In a well pump: a tubular pump body; a piston reciprocable in said pump body; a piston rod connected to said piston; a plurality of expandable and contractible elements coupled to said pump body in fluid flow communication with the interior of said pump body; means connecting one of said expandable and contractible elements with said piston rod for movement therewith; operating oil in said pump body and said expandable and contractible elements; said oil being disposed on opposite sides of said piston; means on said piston rod for connection with means for reciprocating said rod and said piston; an upwardly opening check valve assembly carried by said pump body between said expandable and contractible elements; means embodied in said check valve assembly for forming a seal with said pump body and well tubing in which the pump is positioned; and an intake valve assembly connected to said pump body and disposed below said check valve assembly.

25 17. In a well pump: a tubular pump body; a piston reciprocable in said pump body; a piston rod connected to said piston; a plurality of expandable and contractible elements coupled to said pump body in fluid flow communication with the interior of said pump body; means connecting one of said expandable and contractible elements with said piston rod for movement therewith; operating oil in said pump body and said expandable and contractible elements; said oil being disposed on opposite sides of said piston; means on said piston rod for connection with means for reciprocating said rod and said piston; a tubular member surrounding and circumferentially spaced from said pump body defining therebetween an annular flow passage for well fluid; a check valve assembly carried by said pump body between said expandable and contractible elements; a seat for said check valve assembly located in said tubular member; said tubular member having an intake valve seat below said pump body; and an intake valve assembly on said intake valve seat.
